[57] CLAIM

The original design for a oil-level checking aide for vehicles, as shown and described.

DESCRIPTION

FIG. 1 is a top perspective view of an oil-level checking aide for vehicles showing my new design;

FIG. 2 is a top plan view thereof;

FIG. 3 is a right side elevational view thereof, the left side being substantially a mirror image in appearance; and

FIG. 4 is a front elevational view thereof.

The bottom plan view of the oil level checking aide for vehicles is the same as the top view shown in FIG. 1 (at bottom).
